UNITED STATES PATENT OFFICE.

GEORGE EKLUND, OF ATTLEBORO FALLS, MASSACHUSETTS, ASSIGNOR TO J. F. STURDY'S SONS CO., OF ATTLEBORO FALLS, MASSACHUSETTS, A CORPORATION OF MASSACHUSETTS.

WATCH-BRACELET HOOK.

Application filed June 12, 1925. Serial No. 36,720.

This invention relates to an improved construction of watch bracelet hook for readily detachably connecting the ends of a watch bracelet to the bail of a wrist watch; and 5 the object of this invention is to provide a simple and practical construction of such a hook with the minimum amount of thickness in cross section to be used with a thin strap or bracelet for connecting its ends to 10 the bail of a wrist watch.

A further object of this invention is to provide such a hook having a body portion which may be formed of precious metal and a separate and independent spring 15 member which may be formed of a less expensive spring metal such as steel or the like having the maximum resiliency, the parts being so formed that they are extremely simple to assemble and locked together 20 by simply folding one part of one over that of the other and without the use of solder.

A further object of the invention is to form the bail portion of the hook on the 25 spring member as this part is covered by the passing of the bracelet end therethrough, the bail member being offset inwardly so as to bring the outer face of the strap practically flush with the outer 30 face of the body portion.

With these and other objects in view, the invention consists of certain novel features of construction, as will be more fully described, and particularly pointed out in the 35 appended claims.

In the accompanying drawings:

Figure 1 is a side elevation illustrating my improved form of hook as being employed for attaching one end of a band 40 form of bracelet to the bail of a wrist watch.

Figure 2 shows the body of the hook member as blanked from sheet stock.

Figure 3 shows the blank as folded into 45 position and ready to receive the tongue member.

Figure 4 is a perspective view of the tongue member before being positioned in its body portion.

50 Figure 5 is a view of the under side of the hook showing the tongue member as secured in position in the body portion thereof.

Figure 6 is a central sectional elevation 55 of the hook.

It is found in the practical construction and operation of bracelet hooks of this character, of advantage to provide a hook which is very thin in construction and one in which the body member may be formed 60 of precious metal, such as platinum, gold and the like and to form the hook-closing tongue member of steel or other less expensive and more resilient metal and to lock the two members together without the use 65 of solder, also to form the bail portion on the tongue member to which the end of the bracelet strap may be connected, and the following is a detailed description of the present embodiment of my invention and 70 showing one means by which these advantageous results may be accomplished.

With reference to the drawings, 10 designates the body of the bracelet hook which is provided with rearwardly turned side 75 flanges 11 notched at their edges at 12, the forward end of the body being provided with a shank portion 13, the extremity of which is folded back into hook form as at 14, the rear end of this body being provided with a bendable finger 15 for the purpose presently described.

This body is formed of sheet stock usually of the more precious metals such as platinum, gold and silver, and is, therefore, 85 relatively soft and has little spring or resiliency.

In order to provide a hook-closing tongue member for the bracelet hook, I have formed the tongue member 16 preferably of steel 90 or other more resilient and less expensive metal, the same being provided with laterally-extending shoulder portions 17 adapted to fit into the notches 12 in the body flanges and the rear end of this tongue member is 95 offset slightly inwardly and has a bail portion 18 extending rearwardly of the body member, the same being punched out as at 19 to provide an opening to which the end of the bracelet band may be connected and 100 is offset rearwardly to bring the attaching bracelet flush with the front face of the body portion.

In order to lock this tongue with its shoulder 17 in the notches 12 of the body 105 portion, I fold the finger 15 through the eye 19 of the bail 18 and over the edge of the tongue thereby anchoring the shoulders 17 in these notches and at the same time firmly securing the rear of the tongue to 110

offer suitable resistance for returning the free end of the tongue to closed position on the inner face of the hook after it has been bent inwardly therefrom.

5 My improved watch bracelet is very simple and practical in construction, may be readily assembled by unskilled labor and the parts locked together by simply bending the finger 15 over the end of the tongue and 10 entirely without the use of solder.

The foregoing description is directed solely towards the construction illustrated, but I desire it to be understood that I reserve the privilege of resorting to all the mechanical changes to which the device is susceptible, the invention being defined and limited 15 only by the terms of the appended claims.

I claim:

1. A watch bracelet hook comprising a 20 body member having a hook-shaped end portion, a separate spring tongue member in said body and fixed relative thereto for closing said hook portion and having a bail integral therewith to which the bracelet end 25 may be secured.

2. A watch bracelet hook comprising a body member having side flanges and a hook-shaped shank portion, a spring tongue between said flanges for closing said hook portion 30 and having a slot forming a bail member integral with said tongue to which the bracelet end may be connected, said bail member being offset out of the plane of said tongue.

3. A watch bracelet hook comprising a 35 body member having side flanges and a shank portion with a hook-shaped end, a spring tongue in said body between said flanges for closing said hook and having an angularly-

disposed portion lying against said body, 40 and a finger integral with said body to be folded over said angularly-disposed portion to secure the same to the body member.

4. A watch bracelet hook having a body portion with notched edge flanges and 45 formed of sheet metal with one end folded into hook form, a separate broad faced hook-closing tongue member of sheet spring stock having a portion at an angle thereto and cut away to form shoulders extending into 50 said flange notches, and a portion of the body folded over that of said tongue to lock its shoulders in their notches.

5. A watch bracelet hook comprising a body member having a shank with a hook-shaped end, side flanges on the edges of said body undercut at their distal end from the hook, a spring tongue between said flanges having shoulders extending into said undercut portions and engaging said flanges, and 60 a finger on said body folded over a portion of said tongue to lock said shoulders in their undercut portions.

6. A watch bracelet hook comprising a body member having a shank with a hook-shaped end, side flanges on the edges of said body notched at their distal end from the hook, a spring tongue between said flanges having shoulders extending into said notches in said flanges, a bail on the end of said 70 tongue to which the bracelet end may be attached, and an integral finger on the body folded through the bail opening and over a portion of said tongue to hold the shoulders thereof in their notches.

In testimony whereof I affix my signature.

GEORGE EKLUND.
